(57) **CLAIM**

The ornamental design for an image sensor for scanner, as shown and described.

DESCRIPTION

FIG. 1 is a front, top, and left side perspective view of an image sensor for scanner showing the first embodiment of our new design;

FIG. 2 is a rear, bottom, and right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a part of FIG. 1 thereof;

FIG. 10 is an enlarged view of a part of FIG. 2 thereof;

FIG. 11 is an enlarged view of a part of FIG. 3 thereof; and,

FIG. 12 is an enlarged left side view thereof.

Broken lines and unshaded portions contained within broken lines depict exemplary elements of the image sensor that are shown for illustrative purposes only and that form no part of the claimed design. Dotted and dashed lines represent boundaries between the portions intended for registration as a partial design and the other portions.
